UNITED STATES PATENT OFFICE.

JAMES REED, OF ALTOONA, PENNSYLVANIA.

FROG.

SPECIFICATION forming part of Letters Patent No. 269,711, dated December 26, 1882.

Application filed September 20, 1882. (No model.)

To all whom it may concern:

Be it known that I, JAMES REED, of Altoona, county of Blair, and State of Pennsylvania, have invented new and useful Improvements in Frogs, Switches, &c.; and I do hereby declare that the following is a full and exact description of the same, reference being had to the accompanying drawings, and to the letters of reference marked thereon.

10 This invention is designed to prevent the injury which is done to frogs, safety castings or blocks, and switches ordinarily by the passage over them of wheels having worn tires or treads; and it consists broadly of a frog, safety-casting, or switch having upon its upper bearing-surface a groove or cut-away place corresponding in form with the outline of the projecting portion of a worn tire or tread, as will be fully described hereinafter.

20 In the drawings, Figures 1 and 2 represent a plan and sectional elevation of an ordinary frog modified in the manner prepared; Fig. 3, a sectional elevation of a safety-casting modified in like manner; Figs. 4 and 5, a plan and 25 sectional elevation of a split switch, also modified in like manner.

To enable others skilled in the art to make my improved frogs, &c., I will proceed to describe fully the manner of constructing the same.

30 A, Figs. 1 and 2, represents the main rail leading to the frog, which is of the usual well-known construction.

B represents the sliding rail, leading to the frog, the upper bearing-surface of which is cut away in lines parallel to the main track, as shown in Fig. 1, to a proper depth, as shown in Fig. 2.

C represents the main track-rail, leading to the frog from the opposite side, which is cut away in a similar manner.

D, Fig. 2, represents a car or engine wheel, the tire or tread of which is so worn as to have a portion, d, projecting below its main bearing-surface d', as shown. By means of the described construction the wheel D is permitted 45 to pass the frog without causing the slightest injury, the cut-away place affording proper space for the projection d of the worn tire.

E, Fig. 3, represents a safety-casting of the "Wharton switch," modified in form for the same purpose. F, Figs. 4 and 5, represents a split switch, in which the rail to siding is modified in form for the same purpose. These modifications may be effected in frogs and rails in use by cutting the same properly in a planer; 55 but it is possible of course to introduce these features when the parts are first made.

The great advantage resulting from the employment of this invention is that the serious damage caused ordinarily by the passage of 60 badly-worn wheels over the road is entirely prevented.

Having thus fully described my invention, what I claim as new, and desire to secure by Letters Patent, is—

A frog, safety casting or block, or switch-rail having its upper bearing-surface cut away, substantially as and for the purpose described.

This specification signed and witnessed this 11th day of September, 1882.

JAMES REED.
